UNITED STATES PATENT OFFICE.

ERVIN J. KRUCK AND WALTER A. KRUCK, OF NEW YORK, N. Y.

TRACKER FOR MUSICAL INSTRUMENTS AND THE LIKE.

1,192,076.

Specification of Letters Patent. Patented July 25, 1916.

Application filed July 12, 1915. Serial No. 39,262.

To all whom it may concern:

Be it known that we, ERVIN J. KRUCK and WALTER A. KRUCK, citizens of the United States, residing in the borough of Brooklyn of the city of New York, in the county of Kings, in the State of New York, have invented certain new and useful Improvements in Trackers for Musical Instruments and the like, of which the following 10 is a specification, reference being had to the accompanying drawings, which form a part hereof.

This invention relates to devices for correcting or preventing the lateral displacement of the music sheet as it passes over the tracker-bar of an automatic musical instrument or piano player for the purpose of insuring and maintaining accurate registration of the perforations of the music sheet 20 with the ports or terminals of the tracker-bar. Devices intended to accomplish this same general purpose, and commonly called tracking devices or trackers, at least so far as they have proved satisfactory in practical 25 operation, have thus far depended upon the operation of pneumatic devices (rarely electric devices) for shifting either the music sheet itself, or, as an equivalent, the tracker-bar, to overcome or compensate for the accidental displacement or wandering of the 30 music sheet which would otherwise interfere with the desired accuracy of registration, such pneumatic shifting devices being controlled or having their operation initiated 35 by the slight wandering of the music sheet through intermediate devices, sometimes mechanical or electric, but usually pneumatic, which determine the connection of the pneumatic devices with the vacuum or 40 pressure system. The main object of the invention is to produce a tracker which shall be entirely mechanical in its operation, as distinguished from the trackers which depend directly upon pneumatic devices, mechanical 45 devices, as is well understood, being not only more positive in their action than pneumatic devices, but being also capable of greater sensitiveness and accuracy. Incidental to the attainment of the main object 50 of the invention is also the attainment of simplicity in construction, great accuracy and certainty in operation, and non-liability to derangement by ordinarily careful use.

The invention will be more fully explained hereinafter with reference to the accompanying drawings in which it is illus-

trated as embodied in a satisfactory form and in which—

Figure 1 is a view in front elevation of so much of the tracker-box and appurtenant parts of an automatic player as is necessary to enable the application of the invention to be understood. Fig. 2 is a detail view in elevation, partly in section, and on a larger scale, of some of the parts shown in Fig. 1. Fig. 3 is a detail view in section on the plane indicated by the broken line 3—3 of Fig. 2. Fig. 4 is a detail view in section on the plane indicated by the broken line 4—4 of Fig. 2. Fig. 5 is a detail view, partly in elevation and partly in section, of a portion of the winding-on roll with its appurtenances. Fig. 6 is a view in section on the plane indicated by the broken line 6—6 of Fig. 5.

So far as the character of the invention is concerned, it might be applied to an automatic piano player, or other similar mechanism, of any kind, whether electric or pneumatic, and whether, if the playing devices are pneumatic, the mechanism through which the travel of the music sheet is produced, be driven from an electric, or pneumatic, or other motor. It is also immaterial whether the tracker bar be shifted with respect to the music and winding-on rolls or either of them, or the music rolls or either of them be shifted with respect to the tracker-bar. The invention is most conveniently embodied, however, in a tracker-box mechanism of the general character of that indicated in the drawings, and particularly in Fig. 1, in which the music roll *a* and the winding-on spool *b* are driven through suitable gearing indicated at *c*, from a motor *d*, which may be of any suitable character. The usual clutch connections between the gearing and the spools are controlled, for winding and rewinding, by the operator through suitable devices including, in the construction shown, a lever *e* and link *e'*, and a lever *e''*. It will be understood that during the winding-on, while playing, the winding-on spool *b* is connected with the driving shaft *b'* through the clutch *b''* and that for the re-wind the music spool *a* is operatively connected to the motor while the clutch *b''* is open, the parts being then in the positions indicated in Figs. 1, 2, 3 and 4. The rolls *a* and *b* are not movable axially in this construction, but the tracker-bar *f*, the ports of which

are connected by tubes f' with the player pneumatics, as usual, is mounted in the tracker-box so as to be movable freely in an endwise direction, being shown as hung by links f^2 from brackets f^3 . Provision is made, as will now be described, whereby any wandering or lateral displacement of the music sheet g , in its travel from the music roll a to the winding-on roll b , is immediately accompanied by a corresponding movement of the tracker-bar f , so that accurate registration of the music sheet and the tracker-bar is always maintained.

Adjacent the edge of the music sheet and preferably close to the tracker-bar f is mounted a detector h , preferably in the form of a sleeve grooved circumferentially, mounted to move freely, both in a longitudinal direction and rotarily, on a spindle h' held in the end frames of the tracker-box, the detector being held gently against the edge of the music sheet by the weight of certain connected parts as hereinafter explained or, if desired, by a light spring which is not shown. The circumferential groove h^2 of the sleeve is engaged by a finger l which is provided at its end with a ball l' and is extended downwardly from a spindle or rock-shaft l^2 mounted freely in bearings in a stud l^3 secured on the frame of the mechanism and in a bracket l^4 secured to the stud. A forked arm l^5 is also secured to the spindle l^2 , extending horizontally. Supported freely by the forked arm l^5 is a shifting lever l which may move up or down with the movement of the arm l^5 , as it is moved or is permitted to move under the influence of the weight of the lever l by the detector h , which follows the edge of the music sheet g in its wandering, being pressed to the right when the edge of the sheet wanders to the right and following the edge of the sheet to the left as it wanders to the left. The lever l has a spherical bearing l^6 in a cylindrical sleeve l^7 , a pin l^8 fixed in the spherical bearing l^6 entering slots l^9 in the sleeve so as to prevent the twisting of the lever l while permitting it to move upward and downward freely.

At its upper end the lever l has a spherical bearing l^6 in a cylindrical socket l^4 secured to the longitudinally movable tracker-bar f . As the lever l is swung in one direction or the other by the means herein-after described and acting through the lower end of the lever, the tracker-bar is moved correspondingly, but in the opposite direction, and at the same time the lever is free to be moved up or down by the detector-controlled arm l^5 for the purpose of varying the extent of movement of the tracker-bar, as hereinafter explained.

At its lower end the lever l has a spherical roller bearing l^6 which enters the groove l^9 of a cam m which is mounted on the hub of

the winding-on roll b . The cam m is formed preferably as shown in detail in Figs. 5 and 6, comprising a sleeve hub m' mounted somewhat freely on the hub b^3 of the roll b , with a conical flange m^2 , which is recessed radially on its convex surface, as indicated at m^3 , and a corresponding conical flange m^4 , recessed radially on its concave side, as at m^5 . The two conical flanges form between them a circumferential cam slot, inclined with respect to the axis of rotation, that is to say, a cam slot with parallel but conical side walls. Clearance spaces are formed at intervals by the registering radial recesses m^2 and m^5 . The hub m' is retained in place on the hub b^3 by a keeper m^6 , and the flange m^4 is retained tightly in place on the hub m' by a keeper m^7 which is threaded on the hub m' and clamps the hub of the flange m^4 tightly against a roller of the hub m' . The keeper m^7 constitutes one member of a clutch, having holes m^8 to receive the pins n' of the movable member n of the clutch. The latter is grooved circumferentially as at n^2 for engagement by a pin e^3 carried by the secondary lever e^2 , connected by the link e' with the clutch lever e which operates in the usual manner the winding-on clutch e^4 , so that when the winding-on clutch is closed the cam m rotates with the roll b and when the winding-on clutch is open, for the re-wind, the cam m is released from the roll b and does not rotate therewith. It is desirable that the cam m shall be stopped, when it is released from the roll b , for the re-wind, in a definite position, with the spherical roller bearing l^6 of the shifting lever l in one of the clearance spaces formed by the radial recesses m^2 and m^5 . Accordingly the hub of the flange m^4 is provided, at proper points, with radial pins m^9 and on a fixed member of the frame is pivoted a latch o which is notched on its under side, as at o' ; the clutch lever e^2 is provided with an pin e^5 which, in the re-wind position of the lever, enters the notch o' thereby permitting the latch o to drop into the path of the pins m^9 and to stop the cam m in a definite position by contact with one of the pins, while the movement of the clutch lever e^2 to the winding-on position causes the pin e^5 , by engagement with the inclined side of the notch o' , to lift the latch o , thereby permitting the cam m to rotate with the roll b .

With the parts in the re-wind position, as represented in the drawings, the cam m is stationary and the tracker is idle, but when the parts are moved to the winding-on position the cam m rotates and the tracker becomes active as it is required to exercise its functions. If then the music sheet wanders slightly to the right, the detector h is also moved to the right and, through the

spindle k^2 with its arms, the shifting lever l is raised, raising the spherical roller bearing U in the conical cam slot. The result of this is to move the lower end of the shifting lever to the left and consequently the upper end of the shifting lever and therefore the tracker-bar f to the right in accord with the wandering of the music sheet to the right. It will be understood that the conical cam slot operates as if its walls were formed without the radial recesses, the clearance spaces formed by such radial recesses insuring the perfect freedom of endwise movement of the shifting lever, without danger of binding or jamming. If the music sheet wanders to the left, the detector, influenced by the weight of the shifting lever, follows it to the left and permits the shifting lever to move downward and its lower end to approach the axis of rotation of the cam and therefore to move to the right, with a consequent movement of the tracker-bar to the left.

It will be observed that all of the parts which are moved by edge pressure of the music sheet may be so nearly counterbalanced and at the same time so light in weight while the shifting lever is sufficiently strong to shift the tracker-bar that the actual pressure on the edge of the music sheet is not sufficient to mutilate the edge of the music sheet in any degree whatsoever. Moreover, since there is no appreciable elasticity in any of the parts and the required clearance between the relatively moving parts is so small, the improved mechanism is exceedingly sensitive and the slightest wandering of the music sheet is compensated for immediately by a correspondingly slight movement of the tracker-bar. Substantially perfect registration is therefore insured at all times. It will also be observed that the lever l , herein called a shifting lever, constitutes variable shifting means for changing the relative position of the tracker-bar and the rolls, or one of them, that the cam m is an actuator for such shifting means, and that the spindle k^2 and its associated parts constitute means under the control of the detector for changing the effective relation between the shifting means and the actuator. In a pneumatically controlled tracker the tracker-bar or the rolls, as the case may be, is or are shifted to a greater or less extent by a greater or less collapsing of the actuating bellows, the movement of the free member of the bellows being transmitted to the tracker-bar or the rolls by transmission devices which have no other function, while in the present case there is no bellows to be collapsed to a greater or less extent.

It will be obvious that various changes in details of construction and arrangement of parts might be made to suit different conditions of use and that the invention therefore

is not restricted to the precise construction shown and described herein.

We claim as our invention:—

1. A tracker for automatic musical instruments and the like, comprising a roll, a tracker-bar, one of the two parts last named being relatively movable longitudinally with respect to the other, a detector for contact with the edge of the music sheet, variable mechanical shifting means for shifting the relatively movable part, a mechanical actuator therefor, and means whereby the movement of said shifting means is controlled by the detector.

2. A tracker for automatic musical instruments and the like, comprising a roll, a tracker-bar, one of the two parts last named being relatively movable longitudinally with respect to the other, means for shifting the relative position of said parts, an actuator for said means having a definite movement, a detector for contact with the edge of the traveling sheet, and means under the control of the detector for changing the effective relation between the shifting means and the actuator.

3. A tracker for automatic musical instruments and the like, comprising a roll, a tracker-bar, one of the two parts last named being relatively movable longitudinally with respect to the other, means for shifting the relative position of said parts, a cam for actuating said means, a detector for contact with the edge of the traveling sheet, and means under the control of the detector for changing the effective relation between the shifting means and the cam.

4. A tracker for automatic musical instruments and the like, comprising a roll, a tracker-bar, one of the two parts last named being relatively movable longitudinally with respect to the other, a shifting lever for changing the relative position of said parts, a cam for actuating said shifting lever, a detector for contact with the edge of the traveling sheet, means under the control of the detector for changing the effective relation between the shifting lever and the cam.

5. A tracker for automatic musical instruments and the like, comprising a roll, a tracker-bar, one of the two parts last named being relatively movable longitudinally with respect to the other, a detector for contact with the edge of the music sheet, a shifting lever movable bodily and operatively connected with the relatively movable part, a cam for engagement with the shifting lever and inclined in the direction of bodily movement of the shifting lever, and means whereby the movement of the detector is caused to impart bodily movement to the shifting lever.

6. A tracker for automatic musical instruments and the like, comprising a roll, a tracker-bar, one of the two parts last named

being relatively movable longitudinally with respect to the other, a detector for contact with the edge of the music sheet, a shifting lever movable bodily and operatively connected with the relatively movable part, a rotatable cam provided with an axially inclined, circumferential slot for operative engagement with said shifting lever, and means whereby the movement of the detector will cause to impart bodily movement to the shifting lever.

7. A tracker for automatic musical instruments and the like, comprising a roll, a tracker-bar, one of the two parts last named being relatively movable longitudinally with respect to the other, a detector for contact with the edge of the music sheet, a shifting lever movable bodily and operatively connected with the relatively movable part, a rotatable cam provided with an axially inclined, circumferential slot for operative engagement with said shifting lever, one of the side walls of the slot being recessed to form a clearance space, and means whereby the movement of the detector will cause to impart bodily movement to the shifting lever.

8. A tracker for automatic musical instruments and the like, comprising a roll, a tracker-bar, one of the two parts last named being relatively movable longitudinally with respect to the other, a detector for contact with the edge of the music sheet, a shifting lever movable bodily and operatively connected with the relatively movable part, a cam for engagement with the shifting lever and inclined in the direction of bodily movement of the shifting lever, and a lever in operative engagement with the detector and the shifting lever for effecting bodily movement of the shifting lever with respect to the cam.

9. A tracker for automatic musical instruments and the like, comprising a roll, a tracker-bar, one of the two parts last named being relatively movable longitudinally with respect to the other, a detector for contact with the edge of the music sheet, a shifting lever movable bodily and operatively connected with the relatively movable part, a rotatable cam provided with an axially inclined, circumferential slot, means to stop the rotation of the cam in a definite position, and means whereby the movement of the detector is caused to impart bodily movement to the shifting lever.

10. A tracker for automatic musical in-

struments and the like, comprising a roll, a tracker-bar, one of the two parts last named being relatively movable longitudinally with respect to the other, a detector for contact with the edge of the music sheet, a shifting lever movable bodily and operatively connected with the relatively movable part, a rotatable cam provided with an axially inclined, circumferential slot, one of the walls of the slot being recessed at intervals to form clearance spaces, means to stop the rotation of the cam in a definite position, and means whereby the movement of the detector is caused to impart bodily movement to the shifting lever.

11. A tracker for automatic musical instruments and the like, comprising a roll, a tracker-bar, one of the two parts last named being relatively movable longitudinally with respect to the other, a detector for contact with the edge of the music sheet, a shifting lever movable bodily and operatively connected with the relatively movable part, a rotatable cam provided with an axially inclined, circumferential slot, one of the slots being recessed at intervals to form clearance spaces, a winding-on shaft and clutch, a driving clutch for the cam, the cam being mounted loosely on its shaft, and a lever for operating simultaneously the winding-on clutch and the cam clutch, and means whereby the movement of the detector is caused to impart bodily movement to the shifting lever.

12. A tracker for automatic musical instruments and the like, comprising a roll, a tracker-bar, one of the two parts last named being relatively movable longitudinally with respect to the other, a detector for contact with the edge of the music sheet, a shifting lever movable bodily and operatively connected with an axially inclined, circumferential slot, one of the slots being recessed at intervals to form clearance spaces, a winding-on shaft and clutch, a driving clutch for the cam, the cam being mounted loosely on its shaft, and a lever for operating simultaneously the winding-on clutch and the cam clutch, devices controlled by the movement of the clutch lever to stop the cam in a definite position, and means whereby the movement of the detector is caused to impart bodily movement to the shifting lever.

This specification signed this 8th day of July, A. D. 1915.
